UNITED STATES PATENT OFFICE.

ALEXIS LE BLANC, OF NEW YORK, N. Y., ASSIGNOR TO THE COMPOSITE METAL LATH COMPANY, OF NEW YORK, N. Y., A CORPORATION OF NEW YORK.

WEAVING MECHANISM.

1,379,193.

Specification of Letters Patent.

Patented May 24, 1921.

Application filed July 9, 1915, Serial No. 38,913. Renewed October 12, 1920. Serial No. 416,515.

To all whom it may concern:

Be it known that I, ALEXIS LE BLANC, a citizen of the United States, residing at New York, in the county of New York and 5 State of New York, have invented certain new and useful Improvements in Weaving Mechanisms; and I do hereby declare the following to be a full, clear, and exact description of the invention, such as will enable others skilled in the art to which it appertains to make and use the same.

My invention relates to weaving mechanism. Its object is to provide means by which a positively operated shuttle shall deliver a weft strand directly to a mesh engaging finishing and reforming member of novel construction, without the intervention of guides or a reed. To this end the invention comprises the combinations and 20 tails set forth in the appended claims.

Figure 1 is a perspective taken from one side of the machine.

Fig. 2 is a partial end elevation from the side opposite that of Fig. 1.

25 Fig. 3 is a partial plan view on the side from which Fig. 2 is taken.

Fig. 4 is an enlarged end elevation partly in section and with parts removed from the same side as Fig. 2.

30 Fig. 5 is a partial elevation taken from one side of the detailed improvements to be described.

The positively operated shuttle illustrated is adapted to travel through the plane of the 35 lower rank of warp strands without touching or disturbing any of the strands, being the shuttle described and claimed in a companion application filed by me on March 24, 1915, Serial No. 16,625.

40 In this specification I have applied the same reference letters to various parts which are found also in the companion application so that the identical features may be more readily compared.

45 A shuttle carrier 18 travels on a race-way not here illustrated. It is positively operated by means of a cable 37. The shuttle carries a bobbin 20 whose frame with its operative parts, to be described, is supported 50 on the shuttle carrier.

At each end of the bobbin-frame of the shuttle are a pair of cupped wheels 21 carried by a shaft 22. The lips of the cupped wheels are indicated at 23 and these lips 55 as they rotate engage grooves in the side

of the shuttle-carrier to support the shuttle, the wheels in this general illustration being simply indicated as passing into the top of the groove. The cupped wheels have openings of cuspidal form as shown at 24 so that as the shuttle reciprocates these openings may pass over the successive warp strands without disturbing them.

Secured at one end of each of the shafts 22 is a gear-wheel 25 which engages the 65 pockets of a rack-bar 26 extending across the machine.

The shuttle is to be reciprocated by a cable and power connections such as have been set forth in the companion application. As 70 the shuttle moves from one side to the other the gear-wheels 25 engage the recesses of the rack-bar rotating the cupped wheels 21, so that the openings of the cupped wheels turn over the successive warp strands with- 75 out disturbing them.

On the return movement the rack-bar is slightly shifted as described in detail in the companion application so that its pockets correspond with the succeeding lower rank 80 of warp strands, thus causing a re-timing or readjustment of the cupped wheels to permit them to engage the succeeding rank of warp strands.

As incidental features of the shuttle, there 85 is illustrated a spring brake 50 secured to a spool on the end of the bobbin 20, the opposite end being secured to the frame of the shuttle. The brake has a friction washer 51 of leather or other material at one end, 90 and at the outer end the spring bears a clamping washer or nut 52. As described in the companion application this brake permits the bobbin to pay out the weft strand as it travels backward and forward, the 95 strand being kept taut and the slack being taken up at each end of the stroke.

As the weft strand leaves the bobbin it passes between grooved guide rollers 53 which are carried by a sliding frame 54 located upon the frame of the shuttle and having extending outward rods 55 passing through bearings 56 on the shuttle-frame, and having interposed between the bearings and the pulley frame a coiled spring 57. 100 This spring serves to take up the shock incident to the sudden return movement of the shuttle as it operates backward and forward across the machine.

The harness of the loom is shown at 58 110

and it will be understood that the outer warp strands and the weft strands engage the outer tooth of a toothed rotating cylinder 61. The teeth of this cylinder have inclined 5 faces and are so formed as to first engage and hold the mesh and selvage of the fabric, especially of a wire fabric, and then carry it over and finally permit it to slip off, to be taken by a reel or other structure. The 10 cylinder in this case has the teeth lying side by side so as to form continuous longitudinal channels and broken circumferential channels. The fabric mesh as it is woven is placed along these grooves, the openings 15 of the mesh taking over the several teeth with the result that as the fabric is thus laid out along this rotating cylinder it is reformed and brought to the desired unit arrangement of the mesh, that is, with the 20 four sides of the mesh in proper position for subsequent utilization.

The cylinder 61 lies immediately adjacent the shuttle and the frame of the shuttle is inclined at its outer side so that the weft 25 wire leads directly across and slightly downward to engage the outer tooth of the cylinder 61.

The preceding description is illustrated by Fig. 1 alone. In Fig. 2 and other figures 30 as noted, I have illustrated the side of the machine opposite to that illustrated in Fig. 1 and have shown the means which are provided for the rotation of the roller 61 and its accurate adjustment to the duties required of it.

70 represents the power shaft carrying a driving worm gear 71, operating a gear-wheel 72 to rotate a shaft 73. The gear-wheel 72 has a disk face 74 which may carry 40 a sleeve for the shaft 73 and is secured by nuts 75 which pass through slots 76 so that the wheel may be nicely adjusted to the requisite position before the operation begins. 77 represents the inner part of the sleeve 45 through which the shaft 73 passes carrying at its inner end a gear-wheel 78 which meshes with an idler 79 and finally driving a pinion 80 on the end of the shaft carrying the roller 61.

50 The invention which I have described presents an operative mechanism. I have found that the placing of the weft strand properly along the longitudinal groove of the roller 61 is facilitated by the fact that the shuttle reduces in speed at the end of its travel.

When I have the shuttle close up against the roller 61 at the start I can then put the weft strand well down into the groove. As the shuttle travels across with the weft 60 strand paying out the roller 61 rotates just enough at an ordinary speed to take the weft strand across the bottom of the groove and against the wall of the succeeding teeth. Then as the shuttle slows up there is time 65 for the roller 61 to rotate enough to let the

loop turn about the outside of the next tooth and have the next strand take in against the adjacent wall of that tooth ready to move across that groove space as the shuttle goes back to the other side. In rapid 70 operation, however, this accurate placing of the weft strand with the described mechanism is not always feasible. At a rapid speed it is difficult to get the weft strand well down into the groove and turn firmly 75 and evenly about the tooth. When the weft strand is placed in a rapid operation, the wire, in a sense, is jerked out by the bobbin and is more likely to whip about the first tooth of the roller 61 and pull over the top 80 of the tooth.

I propose to make an advantage of this and to add a device by which I may purposely be negligent of any precision in placing the wire.

I put it about the first tooth of the roller 61 at the start, but it may whip off or not at the end of the movement in view of the additional parts which I have provided, and this improvement also enables me to move 90 the shuttle a little farther away from the roller 61, which in rapid action is more or less desirable.

I have indicated what may happen sometimes in the previously described construction when running at high speed. In addition to this whipping off it will be observed that as the roller 61 rotates and a weft strand is stretched along the length of the roller that end of the roller farthest from the starting point of the weft strand will have traveled farther than the beginning end had traveled when the weft strand was first looped about the first tooth. This would result in laying out the weft strand diagonally along the top of a row of teeth. I have, therefore, provided a device for taking the weft strand at the end of its laying out and carrying it positively forward along the line of rotation of the roller 61 and 100 slightly in advance of the groove it is to enter so that it may take its place accurately in the groove, the slight additional forward movement being compensated by the slight additional rotation of the roller carrying the 105 groove forward. The means which I have employed are under the control of the shuttle.

At 81 is shown a gear-wheel arranged to turn on the shaft of the roller 61. This 120 gear bears a dog 82. The gear-wheel 81 is engaged by a driving gear 83, carried by a short shaft 84 journaled in a bracket 85, attached to the machine. At the end of the shaft 84 opposite to the gear 83 is a partial 125 or mutilated gear-wheel 86. That end of the shaft 84 is journaled in a bracket 87 which carries guide clips 88 through which passes a bar 89 having a section of rack teeth 90 which are engaged by the mutilated 130

gear-wheel 86. At one end of the bar 89 is secured a bent rod 91, whose outer upwardly bent end lies in the path of the shuttle. The opposite end of the bar has 5 secured to it a spring 92 and this spring is likewise secured at the opposite side of the loom to a similar bar, the parts here described being duplicated at that side of the machine. It is the function of the bent rod 10 91 to carry back in one direction the bar 89 when the shuttle moves in that direction, that is, in the illustration of Fig. 1, the spring 92 will draw back the bar 89. It is the positive action of the shuttle upon the 15 bent rod 91 and through the bar 89, the rack teeth 90, mutilated gear-wheel 86 and the gear-wheels 83, 81, that brings up the dog 82 into engagement with the weft strand to carry it over a little beyond the next longitudinal groove, permitting it then to take 20 into that groove, and it is the action of the spring 92 which returns through the parts named the dog 82 to a position below the line of movement of the shuttle, preventing 25 the shuttle from contacting with it as it sweeps across that part of its travel. It is apparent that one action of the bar 89 and its rack teeth 90 upon the mutilated gear-wheel 86 turns its teeth down in a line at a 30 right angle to the movement of the bar 89.

Some provision must be made for presenting the mutilated gear-wheel 86 to the action of the rack teeth 90 when the bar 89 returns after an action on the mutilated 35 gear in one direction. To this end, I have secured on the outer end of the shaft 84 a finger 93 arranged to be engaged by a pin 94 on the side of the rack bar 89. On the return of the rack bar after an operation, the 40 pin 94 will strike the finger 93 and carry over or partially rotate the shaft 84 so that the mutilated gear may be engaged by the rack teeth 90. In line with this idea, I have also secured on a bracket 95 a stop 96 which 45 lies in the path of the end tooth on the gear-wheel 86 to prevent it from dropping down to a lower position than would permit the ready return of the mutilated gear-wheel for prompt engagement by the rack 50 teeth 90.

I thus dispense with any intermediate guides and with the reed or beater because this cylinder directly receiving the mesh from the harness and shuttle performs at 55 once the functions of guides and a reed or beater, placing the wire mesh in the desired relation and holding it there until it is firmly formed and delivered to the succeeding part of the machine. This invention is especially useful in a type of machine such as is illustrated by the application of F. Nossagk, Serial No. 846,408, filed June 20, 1914, for machines for producing composite metal laths, in which it is important that 60 a unit measurement shall be maintained 65

throughout the machine which finally produces a metal lath by putting a coating of clay at the junction of the wires of the mesh, these buttons of clay being afterward burned to form buttons of brick. 70

I have described the specific shuttle shown not as essential to the idea of my invention, but as the preferred form of shuttle especially in the class of weaving just indicated.

In feeding in the outer or selvage strands, 75 which will come together at the first tooth of the roller 61, it is necessary in using the cupped wheels 21, to keep these wires apart. I have therefore provided a pin 98, on the rack bar, so that the outer strand will be 80 kept in the proper position to permit the cupped wheels to pass over, the outer strand being then permitted to join the next strand so that they both meet at the first tooth of the roller 61. 85

Having fully described my invention, what I claim is:

1. In a loom, the combination with a shuttle, of means for receiving directly from the shuttle the fabric mesh as it is woven 90 provided with means for reforming the meshes.

2. In a loom, the combination with a shuttle, of a cylinder having a series of teeth forming longitudinal and circumferential 95 grooves and receiving the warp strands and the weft strands directly without the intervention of a reed or beater.

3. In a loom, the combination with a positively operated shuttle, of a rotating member 100 having a series of teeth for receiving the successive meshes of the fabric directly from the shuttle.

4. In a loom, the combination with a harness and a shuttle, of a cylinder having a 105 series of inclined teeth arranged on the cylinder to form longitudinal and circumferential grooves and receiving the warp strands and the weft strands directly from the harness and the shuttle without the intervention of guides or a reed. 110

5. In a loom, the combination with a shuttle, of a rotating shaft or cylinder having grooves to receive the weft strands, and means to engage a weft strand at one end 115 and force it into a groove.

6. In a loom, the combination with a shuttle, of a shaft or cylinder having a series of grooves to receive the weft strand directly from the shuttle with means for correcting any displacement of the strand on the shaft or cylinder. 120

7. In a loom, the combination with a positively operated shuttle, of a rotating member having a series of grooves for receiving the 125 weft strand directly from the shuttle, a dog, and means for partially rotating the dog to engage the weft strand at one end and place it in a groove.

8. In a loom, the combination with a posi- 130

tively operated shuttle, of a rotating member having a series of grooves for receiving the successive meshes of the fabric directly from the shuttle, and means at each end of 5 the rotating member for engaging and positively placing a weft strand in a groove.

9. In a loom, the combination with a shuttle and a rotating member adapted to receive the weft strand directly from the 10 shuttle, of a gear-wheel on the end of the rotating member carrying a dog to engage the weft strand and means operated directly from the shuttle to positively operate the gear-wheel and the dog.

15 10. In a loom, the combination with a rotary dog or tooth for engaging and placing the weft strand, and a toothed cylinder to receive the strand, of a gear for engaging and driving the dog, a shaft having a mutilated gear on one end and a rack bar engaging 20 the shaft with means for returning the

mutilated gear to a position to be again engaged on the return of the rack bar.

11. In a loom, the combination with rotatable means for engaging and placing a weft 25 strand, and a toothed cylinder to receive the strand, of operating means comprising a shaft, a mutilated gear on the shaft, a rack bar for engaging the mutilated gear, and means for presenting the teeth of the mutilated gear in the line of movement of the teeth of the rack bar.

12. In a loom, the combination with means for taking the two outer warp strands at a single point, of a shuttle having cupped 35 wheels traveling across the warp strands and means for holding the outer warp strands apart at the point of passage of the cupped wheels.

In testimony whereof I have hereunto 40 signed my name.

ALEXIS LE BLANC.
